DISCHARGE CONTROLLING MEANS FOR
DISCHARGE LAMPSChester H. Braselton, New York, N. Y., assignor
to Sirian Lamp Company, Newark, N. J., a cor-
poration of Delaware

Application August 25, 1932, Serial No. 630,379

7 Claims. (Cl. 176—1)

This invention relates to electric lamps and particularly to that type in which a discharge occurs through a gaseous medium.

In my prior filed application, now Patent No. 2,007,919, issued July 5, 1935, I disclosed a new type of lamp in which an electron emitting element is energized by an electric current in the presence of an ionizable gas having a certain pressure. When the conditions are right as to pressure, voltage impressed upon the element, and the character of the gas used, a halo is formed around the element extending from one end to the other and standing out from the filament a distance in the neighborhood of $\frac{1}{4}$ of an inch. As the pressure of the gas is increased in the envelope the halo tends to hug the filament closer while if the pressure is decreased the halo will tend to extend further from the element. Also as the voltage is increased across the electron emitting element there is a tendency for the discharge or halo to increase in diameter while if the voltage is lowered the halo gradually falls back against the filament until it disappears entirely. With a given pressure, therefore, it is necessary to keep the voltage at a constant figure in order to maintain the discharge at a constant size.

It is one of the objects of the present invention to provide auxiliary means for controlling the size of the discharge so that it will not be dependent entirely upon the voltage across the element or the pressure of the gas used.

Another object of the invention is to provide a fixed restricted path for the discharge in a lamp whereby the size of the discharge may be determined independently of the voltage and gas pressure.

Other objects of the invention and objects relating particularly to the construction and assembly of the various parts will be apparent as the description proceeds.

The invention is illustrated in the accompanying drawing in which:

Fig. 1 is a sectional side elevational view of a lamp embodying the invention;

Fig. 2 is a sectional end view taken on the line 2—2 of Fig. 1;

Fig. 3 is a sectional side elevational view of a lamp illustrating another embodiment of the invention;

Fig. 4 is an enlarged side elevational view partly in section of one of the electron emitting elements; and

Fig. 5 is an enlarged sectional elevational view

of another embodiment of the electron emitting element.

In order to properly illustrate the invention a lamp has been shown in Fig. 1 comprising a tubular bulb or envelope 10 formed of suitable transparent material such as glass and having a press 11 at one end and a second press 12 at the other for supporting an elongated electron emitting element 13 on the axis of the envelope. The electron emitting element 13 may be attached to support rods 14 and 15 sealed in the presses 11 and 12 respectively and provided respectively with lead-in wires 16 and 17. While any desirable form of electron emitting element may be used with the invention I may prefer to form said element of a concentrated coil 18 of highly refractory wire such as tungsten, molybdenum, tantalum, or the like, as shown in Fig. 4, with a coating 19 on the surface of the coil formed of a material giving a rich electron emission. This coating may be any of the well known electron emitting materials, such as one or more of the oxides of barium, strontium, calcium, or the like, held on to the coil with a suitable binder which may be driven off when the element is treated prior to sealing off. The coating of electron emitting material may, however, be applied to the individual turns of the wire as indicated in Fig. 5, where the coil 20 is shown coated with the emitting material 21, or the material may be incorporated in the wire itself, as in the case of the well known thoriated tungsten filament which may be made by treating tungstic acid and thorium nitrate.

On one of the presses, as the press 12 which is somewhat thickened for that purpose, I mount a plurality of support rods 22 which extend to about the center of the envelope and adjacent the walls thereof. The ends of the support rods 22 are formed into small hooks 23 and engage a disc 24 of mica, lava, or other suitable insulating material, securing it in a plane substantially perpendicular to the axis of the lamp and with its edges in close proximity with the inner sides of the wall of the lamp. The disc 24 has a hole 25 in the center thereof which has a diameter the same size as the desired discharge and the electron emitting element passes through this hole, as clearly indicated in Figs. 1 and 2. When the discharge occurs it must pass through the hole 25 as the remainder of the disc substantially closes off the interior of the envelope, and the discharge is thus defined by the hole.

The envelope may be filled with a suitable ionizable gas but I may prefer to use one or more

2
of the monatomic gases, such as neon, argon, helium, krypton, and xenon or one or more of certain metal vapors such as the vapors of mercury, caesium, sodium, rubidium, and the like or mixtures of any of such gases or vapors. I have found that the pressure of the gas should be in the neighborhood of 200 mm. of mercury.

With the elements mounted in the envelope as described above, the envelope may be connected to a vacuum pump in the usual manner and an oven may be placed over it to raise the temperature thereof so as to drive out occluded gases from the various parts of the device. The glass and associated parts may be heated to a temperature in the neighborhood of 400° C. or to as high a temperature as the glass will stand without softening in order to remove all of these gases. Current may also be run through the filament to raise the temperature thereof to about 600° C. This heat is continued until a high vacuum of approximately .5 micron is obtained and all of the gases have been removed from the envelope, which is evidenced by no fluorescence when a high tension current from an induction coil is directed against the walls of the bulb. Current may then be increased through the filament and the temperature thereof slowly raised until it is a bright red when the temperature will be about 800° C. This drives out any binder in the electron emitting material and also certain occluded gases which have not yet been removed. The pump continues to remove from the envelope gases which are driven out of elements or other parts.

35 When no more gas is found in the envelope the oven may be raised and the filament heated to slightly less than 1200° C. for a short time to drive out any other occluded gases or vapors which may be left. The pump may then be shut off and a slight amount of an inert gas, such as neon, at a pressure of about 1 mm. may be admitted to the envelope and the filament current turned on again. This causes reddish spots of discharge to appear on the element or other parts 40 of the lamp which gradually increase in size until a diffused glow appears inside of the bulb substantially filling it, and this tends to activate the electron emitting coating to raise the electron emitting efficiency thereof. This process should 45 take about 10 minutes but if white spots appear it is an indication that other gases are present and the envelope should be exhausted again and the process repeated.

When the activation is completed the pump 50 may again be connected to the envelope and the gas pumped out until a high vacuum is obtained. The filament circuit may then be disconnected and the pump turned off and about 50 mm. of neon gas admitted into the envelope followed by 55 about 150 mm. of argon. The bulb may then be sealed off and is ready for use.

When the lamp is connected in a circuit by means of the lead-in wires 16 and 17 the element 60 13 is energized and the temperature thereof raised until it reaches a high rate of electron emissivity. Thereupon the discharge forms, extending outwardly from the filament and passing from end to end thereof through the hole 25 in the insulating disc 24. This discharge consists 65 of luminous gas having the appearance of a bright white flame and its size is determined by the size of the opening in the disc 24. Inasmuch as the hole 25 in the disc determines the size of the path for the discharge it cannot increase any 70 larger beyond the diameter of the hole and is,

therefore, controlled and prevented from carrying more current than is desired.

In Fig. 3 another embodiment of the invention is shown, wherein the disc 26, which is similar to the disc 24, has a hole 27 therein to control the size of the discharge and is mounted directly on the wall 28 of the envelope 29. For this purpose suitable extensions 30 are provided on the inner wall of the bulb at about the center thereof having grooves 31 to receive the disc which may be sprung into position in the glass before the electron emitting element is inserted. The operation of this construction is similar to that already described.

Many other modifications of the invention may be resorted to without departing from the spirit thereof and I do not, therefore, desire to limit myself to what has been shown and described except as such limitations occur in the appended claims.

What I desire to claim and secure by Letters Patent is:

1. In a device of the class described an envelope, a partition having an opening therein mounted within said envelope and dividing said envelope into two compartments interconnected by said opening, an electron emitting element containing one or more oxides of the alkaline earth metals extending through said opening and having one end in one compartment and the other end in the other, and a mixture of neon and argon gases at a pressure of substantially 200 mm. of mercury within said envelope, said electron emitting element being adapted to be energized by the passage of electric current therethrough.

2. In a device of the class described an envelope, a partition having an opening therein mounted within said envelope and forming two compartments within said envelope interconnected by said opening, an electron emitting element containing one or more oxides of the alkaline earth metals extending through said opening and having one end in one compartment and the other end in the other, and an ionizable gas having a pressure of substantially 200 mm. of mercury within said envelope, said electron emitting element being adapted to be energized by the passage of electric current therethrough.

3. In a device of the class described a tubular envelope, a filamentary conductor axially positioned therein, an ionizable gas within the envelope, means including one or more oxides of the alkaline earth metals for producing a halo about said conductor when the conductor is heated to luminous temperatures by the passage of electric current therethrough, said halo being variable in diameter with variation of applied voltage to the terminals of the conductor, and means for maintaining a section of said halo constant with variations of applied voltage, said halo producing means constituting the sole terminal source of the discharge.

4. In a device of the class described a tubular envelope, an axially positioned conductor therein, means including one or more oxides of the alkaline earth metals to produce a halo about said conductor, said halo having a diameter variable with the voltage applied to the terminals of the conductor, and means to maintain a section of said halo uniform in diameter irrespective of variations in the voltage at the conductor terminals, said halo producing means constituting the sole terminal source of the discharge.

5. In a device of the class described a tubular envelope, a filament conductor axially positioned

- therein, an ionizable gas within the envelope, a coating of electron emitting substance containing one or more oxides of the alkaline earth metals on said conductor adapted when heated to cause the formation of a halo about the conductor which halo is variable in diameter with the variation of voltage applied to the conductor terminals, and a plate positioned transversely of said conductor said plate having an aperture including said conductor, said coating constituting the sole terminal source of the discharge.
5. In a device of the class described a tubular envelope, a filament conductor axially positioned therein, an ionizable gas within the envelope, a coating of electron emitting substance containing one or more oxides of the alkaline earth metals on said conductor adapted when heated to cause the formation of a halo about the conductor which halo is variable in diameter with the variation of voltage applied to the conductor terminals, and means for maintaining a section of said halo constant with variation of applied voltage, said coating constituting the sole terminal source of the discharge.
6. In a device of the class described a tubular envelope, a filament conductor axially positioned therein, an ionizable gas within the envelope, a coating of electron emitting substance containing one or more oxides of the alkaline earth metals on said conductor adapted when heated to cause the formation of a halo about the conductor which halo is variable in diameter with the variation of voltage applied to the conductor terminals, and a plate positioned transversely of said conductor said plate having an aperture including said conductor, said coating constituting the sole terminal source of the discharge.
10. In a device of the class described an elongated electron emitting element containing one or more oxides of the alkaline earth metals, a support for said element, an ionizable gas surrounding said element, and a plate of insulating material mounted on said support and provided with an opening through which said element passes, said element constituting the sole terminal source of the discharge.
15. In a device of the class described an elongated electron emitting element containing one or more oxides of the alkaline earth metals, a support for said element, an ionizable gas surrounding said element, and a plate of insulating material mounted on said support and provided with an opening through which said element passes, said element constituting the sole terminal source of the discharge.
